OIL HEATING DEVICE

Henry W. Hildebrand, Jr., and Harold W. Titley,
Denver, Colo., assignors to Oil Service & Engi-
neering Company, Denver, Colo., a corporation
of Delaware

Application March 10, 1931, Serial No. 521,498

1 Claim. (Cl. 126—343.5)

This invention relates to a portable oil heating device. The device has a great many uses a few of which might be mentioned as follows:

(1) Heating a large volume of oil so that this hot oil can be dumped down a well casing to melt and dissolve the paraffins and other heavy oils from the casing and adjacent sands so as to clean and increase the flow of the well and reduce the viscosity of the crude oil therein. When employed for this purpose the device could be used in closed circuit with the well, that is, oil from the well could be returned to the device where it would be heated and returned to the well until the well had reached the desired temperature.

(2) Preparing a volume of hot oil for passage through an oil pipe line for dissolving and cleaning the paraffins and other thickened accumulations from the walls of the pipe.

(3) Heating used crank case oils collected from garages, filling stations, etc., for reclaiming purposes.

(4) Heating crude oil at the well so that various fractionations could be obtained directly so as to obviate a trip to the refinery.

Many other uses can be found for the device, many of which will become more apparent from the following detailed description. It is desired to be understood that all such uses are contemplated in the conception of the present invention.

The principal object of the invention is to provide a device of this character which will be readily portable and which can be efficiently employed to heat relatively large quantities of oil to excessively high temperatures.

Another object of the invention is to combine with the heating portion of the device one or more portable storage reservoirs, the oil in which can be heated from the device, and which can be used to store hot oil should a large volume be required for oil well cleaning purposes.

Still another object of the invention is to so construct the device that all expansion and contraction strains due to temperature changes, will be absorbed so as to not effect the gas and liquid tightness thereof.

A further object of the invention is to so construct the device that a portion of the oil being heated can be used to furnish the fuel for the heating.

A still further object of the invention is to provide a highly efficient heating unit which will enable a maximum absorption of heat to be obtained from the fuel.

Other objects and advantages reside in the detail construction of the invention which is de-

signed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a side elevation of a preferred form of the oil heating device.

Fig. 2 is a vertical section therethrough taken on the line 2—2, Fig. 1.

Fig. 3 is a rear end elevation of the tank portion of the device.

Fig. 4 is a detail vertical section of the heater taken on the line 4—4, Fig. 3.

Fig. 5 also illustrates a section through the flame housing, taken on the line 5—5, Fig. 4.

Fig. 6 is a fragmentary left side elevation of the rearward extremity of the device.

Figs. 2 to 6, inclusive, are drawn to a slightly larger scale than Fig. 1. A typical automobile truck chassis is indicated at 10 with its rear wheels at 11.

The invention comprises a tank 12 of a convenient size to be carried upon the chassis 10. The tank 12 may have any desired shape. It is preferred, however, for structural and efficiency reasons to construct it with a flat bottom and a semi-cylindrical top as illustrated in Fig. 2. One or more (two being illustrated) fire tubes 13 extend within the tank through the rear head parallel with and adjacent to the bottom thereof. The fire tubes 13 are closed at their forward extremities and terminate a sufficient distance from the front head to allow for temperature expansion.

The fire tubes 13 are carried in slide rings 17 supported from the floor of the tank 12 in bracket plates 18. The bracket plates absorb the lateral strains of the tubes 13 but leave the tubes free to expand longitudinally.

A vertical stack 14 extends upwardly from the forward extremity of each tube and projects through a stack sleeve 15. The stacks 14 are welded or otherwise secured in annular heads 16 in the sleeves 15. By carrying the stacks 14 up to a connection at the top of the sleeves 15 a relatively long length of stack is provided which can bend with the expansion of the tubes 13 without imparting disastrous strains. Another reason for using the sleeves 15 is to provide a greater area for absorption of the heat from the gas exhausting through the stack.

The top of the tank 12 is provided with a dome 116

19 covered by means of a removable cap 20 which provides a manhole for cleaning and repairing the interior of the tank. The cap 20 carries a vapor valve 21, a filling valve 22, a safety valve 23, and a pressure gauge 24. A thermometer tube is provided at 25. The tank 12 is also provided with an upper valve 49, a lower valve 50 and a dump valve 51.

10 The rear head of the tank 12 is provided with two annular flanges 26 which are arranged concentric with the fire tubes 13. The flanges 26 receive cylindrical flame housings 27 from which oil burners 28 tangentially project. The flame housings 27 are lined with fireclay or similar 15 heat resisting refractory material 29 and are provided with a flame channel 30. By this construction the flame projected from the burners 28 is caused to whirl in the flame channel 30 and exhaust into the fire tubes 13 in a rapidly whirling, helical path. This causes the flame to cling 20 closely to the walls of the tubes 13 so that a maximum heating effect is obtained upon the surface of the tubes. A peep-hole 31 closed by means of a cap 32, is provided in each of the flame housings 25 to allow the operator to view his flame when desired.

Air is furnished to the burners 28 from a blower 33 driven from a suitable gas engine 34. The blower 33 and the engine 34 are supported 30 upon a frame 35 carried on the rearward extremity of the chassis 10. The blower 33 exhausts into a horizontal air manifold 36, the extremities of which, communicate with the burners 28. Fuel oil is fed to the burners 28 through fuel oil pipes 37 controlled by means of burner valves 38. This 35 fuel oil is obtained from a fuel oil pump 39 which in turn draws the oil from the tank 12 through a fuel oil feed pipe 40 controlled by means of a valve 41.

40 The fuel oil pump 39 is preferably driven from the shaft, indicated at 42, of the blower 33 by means of a suitable belt 43. A circulating pump 44 is also driven from the blower shaft 42 by means of a suitable belt 45. The circulating pump 44 45 intakes from the tank 12 through a control valve 46 and discharges from a discharge pipe 47 controlled by means of a pump discharge valve 48.

When it is desired to heat a relatively large 50 volume of oil, a trailer tank 52 is employed carried upon a trailer chassis 53 which may be hitched to the truck chassis 10 by any suitable draw bar connection 54. The trailer tank 52 is provided with a manhole 55 for cleaning purposes and with a lower circulating valve 56, an upper circulating 55 valve 57 and a dump valve 58.

Operation

The operation of the device for simple heating of oil in the tank 12 can probably be readily understood from the foregoing. Briefly, the burners 28

are ignited and the blower 33 projects a helical blast of flame in the fire tubes 13 which quickly heats the entire volume of oil in the tank.

If a larger volume of oil is required to be heated 80 the discharge pipe 47 is connected to the upper circulating valve 57 of the trailer tank by means of a flexible metal hose 59 and the lower valve 50 of the tank is connected by means of a similar metallic hose 60 to the lower circulating valve 56 of the tank. Hot oil will be circulated by the 85 circulating pump 44 from the tank 12 through the trailer tank 52 and back until the oil in the trailer tank reaches the same temperature as the oil in the tank 12.

If it is desired to dump the oil into an oil well 90 or pipe line the two dump valves 51 and 58 are connected together so that the entire volume of oil can be discharged at once. Should the device be used for circulating hot oil in a well the dump valve 51 is connected so as to discharge into the well and the valve 49 is connected to the discharge of the well pump so that hot oil can be allowed to flow into the well and cool oil pumped out into the tank 12 to replace it.

Should the device be required to pump hot oil 100 into a pipe line or tank it can be connected to the desired apparatus by means of the pump discharge 47.

Should the device be used in connection with a portable still or refinery the vapor outlet valve 21 105 can be connected direct to the still so as to condense the vapors arising from the oil when the desired temperatures are reached. The temperatures can be watched by means of the thermometer tube 25 and controlled by means of the burner 110 valves 38.

While a specific form of the improvement has been described and illustrated herein, it is desired to be understood that the same may be varied, within the scope of the appended claim, without 115 departing from the spirit of the invention.

Having thus described the invention, what is claimed and desired secured by Letters Patent is:—

A device for heating fluids comprising: a tank; 120 a heating tube extending within said tank adjacent the bottom thereof; said tube opening through one end of said tank; a stack arising from the other extremity of said tube and passing to the exterior of said tank; a burner adapted to 125 project a flame within said tube, said tube terminating in spaced relation to the other end of said tank; bracket plates extending upwardly from the bottom of said tank; and slide rings carried by said bracket plates and adapted to 130 slidably support said fire tubes so as to allow longitudinal expansion of said tube.
